Application March 24, 1947, Serial No. 736,636

2 Claims. (Cl. 181—31)

1
This invention relates to speakers of the electromagnetic type. The invention has several aspects and corresponding purposes and accomplishments, which will be set out in connection with the following description of preferred embodiments of the invention.

According to one aspect of my invention I provide a speaker of the cone type with a central rigid diaphragm or dome which is directly physically connected with the actuating element, which is here the vibrating voice coil. This central diaphragm is made in such form as to be substantially rigid in itself, and is accordingly preferably made in the form of a spheric dome. Due to its characteristics, and due to its direct physical connection with the voice coil, it vibrates as a rigid unit and is particularly effective in radiating the higher frequencies. The lower frequencies are radiated both by the central dome and by the surrounding cone diaphragm.

In such a speaker, a horn unit, preferably of the multi-cellular exponential type may be and preferably is associated with the central rigid or dome diaphragm.

The cone diaphragm, which is connected at its inner periphery with the voice coil, is relatively flexible and its outer portions partake less in the vibratory motion of the voice coil as the frequency increases. It is consequently desirable to increase the efficiency with which the energy from the central rigid dome is transmitted and that is effected by associating a horn with that central member.

Such a combination of central rigid diaphragm and surrounding cone, particularly when it includes the efficiency increasing horn, provides a speaker unit of relatively small bulk and simple structure which in performance approaches closely to the performance of much larger and more complicated combinations.

The accompanying drawings show my present preferred form which is illustrative of the various features of my invention. In those drawings,

Fig. 1 is a half-elevation, half-central-section showing my preferred design;

Fig. 2 is a fragmentary front elevation at a reduced scale; and

Fig. 3 is an enlargement of certain portions of Fig. 1.

The speaker structure is symmetric about its longitudinal axis; the half shown in elevation in that figure is therefore a duplicate of the half shown in section.

In the drawings the usual enclosing case is shown at 10 and the usual magnet system is

shown as attached to the back of the case. As here illustrated the field magnet system includes a permanent magnet, although an electro-magnet of course may be used. As illustrated, the permanent magnet is shown at 11 with a front central pole piece 12 at one end and with a surrounding annular pole piece 13 magnetically connected with the other end of magnet 11 by members 14 and 15 forming the usual magnetic circuit. The annular voice coil is shown at 16 in the annular gap between pole pieces 12 and 13. As here shown the voice coil is mounted on and carried by a light tubular member 20, constructed of any suitable material and usually made of impregnated paper. The voice coil and tubular carrier 20 may be considered as making up the magnetically energized actuating element of the speaker.

Voice coil tube 20, in the design shown in the drawings, extends forwardly from voice coil 16 a short distance and carries the rigid diaphragm 21 at its forward edge.

Although diaphragm 21 may be flat or of other shape, it is preferably spherically dome-shaped with its convex face outward, as shown. The diaphragm is composed of some suitable stiff and light material, for instance of some suitable plastic or of a metal such as aluminum or alloy. The dome and tube 20 are preferably of substantially equal diameters and are rigidly secured together at their edges at 22 by cementing or similar attachment. Thus assembled, the dome 21, tubular member 20, and voice coil 16 form a substantially rigid unit which will vibrate substantially as one rigid whole in a direction along the axis of the speaker. Due to the rigidity of the connection between dome 21 and voice coil 16 the dome may be regarded as being rigidly physically attached directly to the voice coil itself. The axial forward extent of tube 20 from the voice coil may be less than that shown in the drawings and may be substantially completely eliminated, so that the dome would then be actually directly connected with the voice coil. The forward extent of tube 20 is however preferred, as that provision spaces dome 21 forwardly from pole piece 12 and also facilitates the connection of cone diaphragm 25 with the tube. The space behind dome 21 is vented by holes 20a through tube 20.

Cone diaphragm 25 may be of any of the usual forms and structures and it is connected with tube 20 independently of the connection of dome 21 to that tube. With such independent connections each of the diaphragms 21 and 25 are actuated directly from the voice coil. As here

shown the cone diaphragm has a flange 26 at its inner periphery cemented to the outer surface of tube 20. It is also held to the tube by the inner flange 27 of an annular member 28 which has its outer periphery secured at 29 to casing 10. The function of annular member 28 is to center tube 20 and the voice coil in proper concentric relation in the magnet gap and at the same time to allow free vibratory movement of those parts along the axis. Member 28 may be of any suitable construction; it is here shown as a thin annulus composed of a molded plastic.

The parts so far described may compose the complete dual-diaphragm speaker, both of the diaphragms 25 and 21 radiating directly without the intervention of a horn. It is preferred, however, to associate a multi-cellular exponential horn with the dome diaphragm 21 in the manner shown in the drawings. The multi-cellular horn unit 30, as shown here, may comprise any suitable number of cells, shown as six. The unit is preferably an integral one formed of some suitable molded plastic. The inner in-put end of the horn unit is secured in a mounting plate 31, and a face plate 32 is also secured to the rear face of mounting plate 31 surrounding the inner input end of the horn unit. The three parts may be secured together in any suitable manner. As here shown face plate 32 is secured to mounting plate 31 by screws 33; and the inner intake end of unit 30 is secured within both plate 31 and plate 32 by cementing.

The inner face of the inner end of the horn, and the inner face of face plate 32 are both formed to a single spheric surface 35 which is concentric with and spaced a short distance forward of dome diaphragm 21, as shown in the drawings. The outer diameter of face plate 32 is preferably about the same as the external diameter of dome 21. Thus the arrangement is such that a thin spheric space is enclosed by face 35 of the horn unit directly forward of the convex face of dome diaphragm 21. Plates 31 and 32, or at least face plate 32, may be considered as forming a part of the horn unit; so that the spheric surface 35 may be considered as being formed directly on the inner end of the horn unit.

The horn unit is supported in the casing by a pair of supports, each shown as comprising a spacer tube 40 and a bolt or screw 41, supporting the supporting plate 31 from the casing. As here shown, the supporting units 40, 41 connect directly with annular casing member 42 upon which the magnet system is directly mounted.

The two supporting units 40, 41 pass through holes 28a provided in member 28. In order to allow member 28 freedom of movement, the holes 28a are made large enough to provide clearance. Clearance holes 25a are also provided in cone diaphragm 25 to pass the supporting units. To seal off the voice coil and the magnet gap against possible entry of dust or other foreign matter which might clog the gap, a soft flexible felt diaphragm is provided at 45, cemented at its edges to extend between cone diaphragm 25 and horn unit 30; and another soft felt sealing diaphragm 46 is placed back of annular member 28, this annular felt diaphragm being attached at its edges to member 28 and having holes which fit the supporting spacer tubes 40 closely.

As before stated, my invention is concerned mainly with the combination of a central rigid diaphragm, rigidly connected with the voice coil,

and a surrounding cone diaphragm which radiates directly; and preferably with an efficiency increasing horn associated with the central rigid diaphragm. The features of preferred constructional detail which have been set out in the foregoing detailed description are typical only and are not to be taken as limitations on my invention except as the following defining claims may so state.

10 I claim:

1. In a speaker of the character described, a single voice coil element of tubular form including a single voice coil adapted to operate in an annular magnetic gap and the element having an outer end beyond the gap, a relatively small and a relatively large diaphragm actuated by the voice coil element, the relatively small diaphragm consisting solely of a rigid dome having an outward convex radiating face of substantially the same diameter as the tubular voice coil element and having its peripheral edge directly and rigidly mounted on the outer end of that element, and the larger diaphragm consisting solely of a relatively flexible annular cone with an outer radiating face directly open to free space, said annular cone coaxially surrounding the tubular voice coil element and the rigid diaphragm and having its inner periphery directly and rigidly attached to the outer end portion of the tubular voice coil element, all whereby the smaller rigid diaphragm and the inner peripheral edge of the cone diaphragm are vibrated together at all frequencies as a rigid unit with the voice coil, and an outer fixed casing structure behind and surrounding the larger cone diaphragm, an expanding horn unit supported with its open intake end in close juxtaposition to and outward of the outer radiating face of the smaller rigid diaphragm, and supporting means for the horn unit comprising mounting studs located outside the voice coil element and extending generally parallel to the axis of that element freely through openings provided in the cone diaphragm, the inner ends of said studs being rigidly mounted on the casing structure behind the cone diaphragm and the outer ends, outward of the cone diaphragm, rigidly carrying the horn unit.

2. Speaker structure as defined in claim 1, and also including an annular flexible sealing diaphragm secured at its inner edge to the horn unit and at its outer edge to the outer face of the cone diaphragm and lying outward of the outer ends of the supporting studs, and another annular flexible sealing diaphragm lying behind the cone diaphragm with its inner peripheral edge connected with the voice coil element, its outer edge secured to the casing structure, and having openings which closely fit the supporting studs.

GEORGE L. CARRINGTON.
